UNITED STATES PATENT OFFICE.

WILLIS H. SARGENT, OF ST. JOHNSBURY, VERMONT, ASSIGNOR TO THE
E. & T. FAIRBANKS & COMPANY, OF SAME PLACE.

DESIGN FOR A BRACE FOR PLATFORM-SCALES.

SPECIFICATION forming part of Design No. 32,954, dated July 17, 1900.

Application filed June 14, 1900. Serial No. 20,369. Term of patent 14 years.

To all whom it may concern:

Be it known that I, WILLIS H. SARGENT, a citizen of the United States, residing at St. Johnsbury, in the county of Caledonia and State of Vermont, have invented and produced a new and original Design for a Brace for Platform-Scales, of which the following is a specification.

My invention relates to a new and original design for braces for platform-scales; and it consists in the design for such brace herein-after described, and referred to in the appended claim.

In the accompanying drawing, which illustrates the invention, the figure represents a front view of the brace embodying my design and showing it attached to a supporting-pilar of the platform-scale.

In the drawing, B represents a curved bracket or brace formed at its lower end with a double scroll, the upper parts of which scroll are connected by the bar C. Projecting upwardly and forwardly from this double scroll are curved bars D, having between them and connected with them a serpentine or zigzag

brace-piece E, one of said bars D at its forward end being curved around and united to the serpentine piece E, as shown at F. Projecting upwardly from the forward end of the brace is the part G, and projecting downwardly from the forward lower scroll portion is the base H.

The essential feature of the design consists of the brace having the double-scroll lower portion, with the upwardly and forwardly projecting curved bars, with the serpentine or zigzag brace between said bars.

Having thus described my invention, what I claim, and desire to secure by Letters Patent, is—

The design for a brace for platform-scales; substantially as shown and described.

In testimony whereof I have hereunto affixed my signature in the presence of two witnesses.

WILLIS H. SARGENT.
